UNITED STATES PATENT OFFICE

1,998,298

ELECTRON DISCHARGE AMPLIFIER
CIRCUITIrvin R. Weir, Schenectady, N. Y., assignor to
General Electric Company, a corporation of
New York

Application February 23, 1933, Serial No. 657,963

5 Claims. (Cl. 179—171)

My invention relates to electron discharge amplifier circuits which are arranged to use a plurality of similar electron discharge tubes. It is sometimes desirable to operate such a circuit, particularly a power amplifier circuit, at a rating which is materially less than the full tube rating of the circuit. For example, the power demand on a four tube amplifier circuit may for various reasons decrease to such a value that it can adequately be supplied by one, two or three tubes only. Obvious economies in operation costs would follow such a reduction in the number of tubes employed particularly in the case of a power amplifier employing modern water-cooled tubes of large capacity. Inasmuch as such an amplifier circuit is very carefully balanced an unnecessary tube or tubes cannot be removed therefrom without readjusting the entire circuit to preserve the balance. One object of my invention is to provide an electron discharge amplifier circuit including apparatus by which the circuit may be quickly and easily converted to one of a lower rating without affecting the balance or tuning of the grid or plate circuits. Another object is the provision of an improved capacitor by the use of which the first mentioned object is accomplished.

In accordance with my invention when the capacity or rating of an amplifier circuit having tubes connected in parallel is to be reduced I substitute for one of the tubes in parallel a double capacitor having the same electrical constants as the tube it replaces and preferably also substantially the same dimensions as that tube. This capacitor which I shall term a dummy tube capacitor is constructed to fit into and to be secured in the socket of the tube it replaces, its three electrodes being connected in the circuit similarly to the tube terminals. Having the same capacitance and lead inductance values as the tube it replaces the dummy tube capacitor when substituted in the circuit does not disturb the balance or tuning of the circuits. Also by constructing the dummy tube capacitor to correspond in form with a tube the capacitor is better adapted for use where the space available is limited to that required by a tube.

My invention will be better understood from the following description taken in connection with the accompanying drawing, and its scope will be pointed out in the appended claims.

Fig. 1 is a cross-sectional view showing the dummy tube capacitor comprising one feature of my invention; Fig. 2 is a circuit diagram of a well-known form of power amplifier; Fig. 3 is a

similar circuit diagram of the same power amplifier but embodying another feature of my invention; and Figs. 4 and 5 are circuit diagrams of modified forms of power amplifier also embodying my invention.

Referring first to the dummy tube capacitor C shown in Fig. 1, the water jacket 1 together with the inlet and outlet pipes 2 and 3 for the cooling water and the securing screws 4 are parts which are regularly employed for supporting and cooling the power amplifier tubes such as are employed in power amplifiers of relatively large capacity. The dummy tube capacitor which I have devised is constructed and arranged to be substituted for or to replace an operative amplifier tube in the event that the tube is not required. The dummy tube capacitor as shown in Fig. 1 comprises the base member 6 whose form is similar to the corresponding member of the amplifier tube for which it is substituted and hence fits into the water jacket 1 where it may be clamped in place by the tube clamping screws 4. Secured to base 6 is the dummy plate member 7 which is provided with passages 8 therethrough for the circulation of cooling water. Secured also to the base 6 is the hollow support 9 of insulating material such as glass or quartz to whose upper end is secured the dummy grid member 10. This member is in the form of an inverted cup which surrounds the dummy plate member 7 but is spaced therefrom and the space is filled with a suitable solid dielectric material such for example as sulphur. By this construction the grid member 10 is suitably insulated against the high potential of the plate member 7 and the capacitance between those members is the same as the grid-plate capacitance in an amplifier tube for which the capacitor is substituted. Dummy cathode member 12 having a cup-shape form is supported on the grid member 10 by means of the insulator 13. This member 12 surrounds the grid member 10 and is spaced therefrom, the dielectric between these members being air. The capacitance between members 10 and 12 is the same as the grid-cathode capacitance in the amplifier tube for which the dummy tube capacitor is substituted. Suitable terminals 14, 15 and 16 are provided for members 7, 10 and 12 respectively for the convenient connection of those members in the circuit when the capacitor is substituted for an amplifier tube. Inasmuch as the space allotted to the apparatus of a power tube amplifier 7 often is limited to the absolute necessities thereof the dummy tube capacitor which I have devised is

constructed to conform substantially to the dimensions of an amplifier tube for which it is to be substituted thereby facilitating its use in the amplifier circuit.

5 In order better to understand my invention I have shown in Fig. 2 a well-known form of push-pull power amplifier circuit 19 embodying two amplifier tubes connected in parallel in each side of the push-pull circuit. As shown in this figure the input circuit 20 connects through the input transformer 21 with the grids of amplifier tubes 22 and 23 in one side of the push-pull circuit and with the grids of the amplifier tubes 24 and 25 in the other side thereof. The plates 10 of the amplifier tubes connect through the output transformer 26 with the output circuit 27 and with the source of supply 28 of plate voltage. The push-pull circuit is shown provided with various tuning circuits which being well 15 known in the art will not be described. With all four tubes 22-25 inclusive in place the four-tube circuit shown in Fig. 2 is adapted for full capacity use.

In Fig. 3 I have shown the same circuit modified by the substitution of a dummy tube capacitor such as shown in Fig. 1 for each of two of the amplifier tubes thereby reducing the capacity of the amplifier from a four-tube circuit to a two-tube circuit. Thus in Fig. 3 it will be seen that 20 amplifier tubes 22 and 25 have been replaced by the dummy tube capacitors C. Since the grid-plate and the grid-cathode capacitance and inductance of the dummy tube capacitor is the same respectively as the grid-plate and the grid-cathode capacitance and inductance of the amplifier tube which it replaces, the substitution of the dummy capacitors in the circuit does not disturb the carefully balanced and tuned condition 25 of the circuits. Moreover since the dummy tube capacitor is constructed to fit the amplifier tube holder the exchange of a tube for a capacitor may be made quickly and conveniently, there being no circuit adjustments necessary except that of connecting the terminals of the capacitor to 30 the circuit terminals to which the tube terminals previously connected. Likewise a tube may be substituted for a dummy tube capacitor with equal speed and convenience.

The modified form of my invention shown in 35 Fig. 4 is similar to that of Fig. 3 except that each side of the push-pull circuit is adapted to include one amplifier tube, instead of two. As illustrated by Fig. 4, one side of the circuit contains amplifier tube 39; in the other side of the 40 circuit the tube has been replaced by the dummy tube capacitor C.

The modified form shown by Fig. 5 is a single 45 circuit 29 which is adapted to employ two amplifier tubes in parallel. The circuit is represented as including the single amplifier tube 30 and the dummy tube capacitor C substituted for the other tube. The input circuit is shown as including the transformer 31 and the output circuit as including the transformer 32, the plate 50 voltage in this case being shown as applied by the battery 33.

The dummy tube capacitor not only is useful 55 to reduce the power of the amplifier circuit but is useful in the construction of an amplifier circuit to balance the circuit so that a push-pull load may be taken from it. The power required from an amplifier circuit may be such that a single amplifier tube is sufficient but if a transmission line load must be taken from the am-

plifier the use of a dummy tube capacitor solves the problem of balance of that load.

I have chosen the particular embodiments described above as illustrative of my invention and it will be apparent that various other modifications may be made without departing from the spirit and scope of my invention which modifications I aim to cover by the appended claims.

What I claim as new and desire to secure by Letters Patent of the United States is:

1. An electron discharge amplifier circuit constructed and arranged to employ a plurality of electron discharge tubes having the same electrical characteristics and connected in circuit with each other, an operative electron discharge tube and a dummy tube capacitor connected in said circuit in parallel with each other, said dummy tube capacitor having its electrodes spaced by a solid dielectric and having the same electrical characteristics as said operative discharge tube.

2. An electron discharge amplifier circuit having portions operative respectively on the positive and the negative half waves of the alternating current supply, each of said portions being constructed and arranged to employ a plurality of electron discharge tubes having the same electrical characteristics and connected in parallel with each other, an operative electron discharge tube and a dummy tube capacitor connected in each 25 of said portions in parallel with each other, said dummy tube capacitors having the form of said operative tubes and provided with solid dielectrics at atmospheric pressure and having the same electrical characteristics as the discharge 30 tube with which they connect in parallel.

3. A dummy tube capacitor constructed to replace an electron discharge tube in an amplifier circuit and having the same electrical constants and substantially the same dimensions as said 40 tube, said dummy tube capacitor comprising a dummy plate member, a dummy grid member surrounding said plate member and separated therefrom by a solid dielectric, an outer dummy cathode member spaced from said plate member, 45 and a base member connected with said plate member and constructed to fit the socket of said tube.

4. A dummy tube capacitor constructed to replace an electron discharge tube in an amplifier 50 circuit comprising a central dummy plate member, an inverted cup-like dummy grid member enclosing the upper end of said plate member, a solid dielectric therebetween, an inverted cup-like dummy cathode member supported over and 55 spaced from said grid member, and a base arranged to seat in and to be secured to the tube socket.

5. A dummy tube capacitor constructed to replace a water cooled electron discharge tube in 60 a power amplifier circuit and to have the same electrical constants and substantially the same dimensions as said tube comprising a core-like dummy plate member, a base member secured thereto and constructed to fit into the tube 65 socket, an inverted cup-like dummy grid member enclosing the upper end of said plate member, sulphur dielectric therebetween, a glass enclosing member secured at opposite ends respectively to said grid and base members, and an inverted cup-like dummy cathode member secured over said grid member and spaced therefrom by an air dielectric.

IRVIN R. WEIR.
